UNITED STATES PATENT OFFICE.

HENRY J. LAWSON, OF LONDON, ENGLAND.

VELOCIPED.

SPECIFICATION forming part of Letters Patent No. 561,798, dated June 9, 1896.

Application filed April 11, 1894. Serial No. 507,106. (No model.) Patented in England January 18, 1894, No. 1,120; in France March 23, 1894, No. 237,271, and in Belgium March 30, 1894, No. 109,266.

To all whom it may concern:

Be it known that I, HENRY JOHN LAWSON, a citizen of England, residing at No. 7 Lothbury, in the city of London, England, have invented certain new and useful Improvements 5 in Velocipedes, (for which I have obtained Letters Patent in Great Britain, dated January 18, 1894, No. 1,120; in France, dated March 23, 1894, No. 237,271, and in Belgium, dated 10 March 30, 1894, No. 109,266,) of which the following is a specification.

My invention relates to the construction of a velocipede by which I attain the following objects: The rider can safely run the velocipede as a unicycle on one wheel, balancing himself with ease, so that his weight is directly over the axle, thereby insuring effective driving without slip and loss of power consequent on slip. The rider also can sit erect in 20 an attitude much more conducive to health and comfort than the stooping attitude which riders of safety-bicycles have generally to assume. As there is only one main wheel requiring an elastic tire, as the front and back 25 wheels are small and not necessarily having elastic tires, the weight and cost of the velocipede are much less than of those which have two wheels with their expensive tires. The parts are so arranged, as will be hereinafter 30 explained, that the whole velocipede can be packed up for transport in small compass scarcely exceeding the bulk of the wheel; and this arrangement of the parts permits also of 35 their being so set that the velocipede can stand by itself.

I shall describe the construction of velocipede according to my invention, referring to the accompanying drawings.

Figure 1 is a side view. Fig. 2 is a front 40 view of a velocipede according to my invention. Fig. 3 is a vertical section of the fork-bearing. Fig. 4 is a section showing the attachment of one of the steering-handles. Fig. 5 shows a detail hereinafter referred to.

On the backbone A, I mount the saddle S, 45 which may be provided with springs arranged in any known manner, and to the backbone I joint, preferably with ball-bearings, as shown in Fig. 3, the steering-fork F, and also a front frame B, which is made integral with the fork F at the joint and is stayed to the fork by ties b, which may also be integral with the fork.

In holes formed in the shoulders of the fork at K, Fig. 4, are secured the ends of the steering-handles H, which can be turned more or less obliquely up and secured in any desired position by spring-catches L. The steering-arms are bent, as shown by the dotted lines H' in Fig. 1, so as to clear the legs of the rider. They may also be withdrawn from their sockets K and turned backward, if desired.

To the lower parts of the forks F are jointed bearers for the pedal-axes P, and these bearers can, by means of screws and nuts p, be strained more or less away from the main axle 65 D, so as to tighten the driving-chains C. To the end of the backbone A, I secure in a screw-clamp, such as is shown in section in Fig. 5, a curved arm E, which carries the back wheel W. The upper end of the arm E is made with 70 two or more grooves with several holes in each groove.

By partly unscrewing the setting-screw I can raise or lower the arm E and turn it more or less around, and then by screwing in the 75 screw so that its point enters one of the holes in the groove I can fix the arm E in the position shown or that indicated by the dotted lines E'. In the lower end of the front frame B, I in like manner clamp an arm M, which 80 carries the front wheel N, mounted as a caster. The wheel N, being mounted as a caster, will readily take the direction of travel when it touches the ground. To keep it generally in alinement with the main wheel, it may have 85 a spring n, arranged to bear on a flat at the front side of its collar.

As in respect of the arm E, so I can raise or lower the arm M or turn it around to the dotted position M'. The back wheel W and 90 the caster N may be so adjusted that they do not reach the ground when the rider balances himself, so that the velocipede then operates as a unicycle. By turning the arms E of the back wheel and M of the caster out of line 95 with the driving-wheel the velocipede can stand at rest, as on three supports. Also by turning these arms around to the dotted positions E' and M', so as to bring them against the main wheel, and also turning down the 100 steering-handles to the position H', against the forks, the whole velocipede is brought into a compact form for transport.

Having thus described the nature of my

said invention and the best means I know for carrying the same into practical effect, I claim—

1. In a velocipede, the combination of the backbone A, the steering-fork F carrying the main driving-wheel and mounted to turn on a vertical axis in the forward end of the backbone, the front frame B having its upper end integral with the fork, the stays or ties b rigidly connecting the lower portions of the fork and front frame, and the curved arms E and M each carrying a small wheel and clamped, respectively, to the lower ends of the backbone and front frame in which said arms have a turning and vertical adjustment substantially as described.

2. In a velocipede, the combination with the single main driving-wheel, the backbone A, the front frame B, and the steering-fork F rigidly connected to the front frame and mount-

ed therewith to turn on a vertical axis in the forward end of the backbone, of the curved arm E carrying a small back wheel W, the curved arm M carrying a small front wheel N, said arms mounted in clamps on the lower ends of the backbone and front frame, respectively, and each having a series of annular grooves provided with a series of holes, and set-screws adapted to engage the holes in said grooves and permit a vertical and turning adjustment of the arms carrying said back and front wheels, substantially as described.

In testimony whereof I have signed my name to this specification, in the presence of two subscribing witnesses, this 29th day of March, A. D. 1894.

HENRY J. LAWSON.
